UNITED STATES PATENT OFFICE.

ANTON B. MENSING, OF NEW YORK, N. Y.

CIGARETTE-EXTINGUISHER.

1,366,675.

Specification of Letters Patent. Patented Jan. 25, 1921.

Application filed November 1, 1919. Serial No. 334,986.

To all whom it may concern:

Be it known that I, ANTON B. MENSING, a citizen of the United States, residing at New York, in the county of New York and State of New York, have invented a new and useful Improvement in Cigarette-Extinguishers; and I do hereby declare the following, when taken in connection with the accompanying drawings and the characters of reference marked thereon, to be a full, clear, and exact description of the same, and which said drawings constitute part of this application, and represent, in—

Figure 1, a view in side elevation, showing my improved cigarette-extinguisher as applied to a combined ash-tray and match-box holder.

Fig. 2, a broken view thereof in vertical section.

Fig. 3, a view thereof in transverse section on the line 3—3 of Fig. 2.

My invention relates to an improved cigarette-extinguisher for use as a smoker's accessory, the object being to produce a simple, convenient and effective device whereby cigarette smokers may readily extinguish the burning butts of cigarettes for quickly and completely extinguishing the same without staining or burning the fingers and without making the "mess" which usually follows the crushing of a cigarette stub.

With these ends in view my invention consists in a cigarette-extinguisher comprising an anvil and a plunger and having certain details of constructions as will be hereinafter described and pointed out in the claims.

In carrying out my invention as herein shown, it is applied to a combined ash-tray and match-box holder of the familiar type though I do not limit myself to making this particular application of my invention. The circular cup-like ash-tray 4 is formed in its center with a concentric upstanding truncated cone 5 the circular flat top of which is located substantially in the plane of the edge of the cup and forms the anvil 6 of my device. Two upstanding transversely bowed arms 7 located opposite each other rise from opposite points on the edge of the said anvil and support a sleeve 8 mounting a plunger 9 the flat lower face of which substantially corresponds in diameter to the diameter of the anvil and the lower end of which has an annular flange or stop-shoulder 10 co-acting with a flange 11 formed at the lower end

of the sleeve 8 for preventing the plunger from being pulled upward out of the sleeve. Wide clearance-spaces 12 located opposite each other between the edges of the supports 7, provide for the introduction of the burning end of a cigarette such as 13, between the anvil and the plunger as shown in Fig. 1.

The upper end of the plunger 9 mounts a U-shaped match-box holder consisting of a frame or cage 14 containing a rectangular retaining-foot 15 over which the shell or slip-cover of a standard match-box is set in the ordinary way.

In using my improved device, the match-box holder is grasped by the fingers and the plunger 9 lifted above the anvil 6 sufficiently for the insertion of the burning end of a cigarette through either one of the openings 12 into the space between the anvil and the plunger which latter is now crowded down upon the cigarette by downward pressure upon the match-box holder. The cigarette thus immediately extinguished, is then brushed into the ash-tray 4. If preferred, the plunger 9 may be made to fit so snugly in the sleeve 8 that it will be frictionally held therein or a spring may be provided for normally holding the match-box and plunger in their elevated positions above the anvil. I am aware that it is old to combine a match-box holder with an ash-tray, and do not claim such a construction broadly, nor do I broadly claim the combination with an ash-tray of a cigarette-extinguisher comprising two jaws of which one is movable with respect to the other, for crushing a cigarette introduced vertically between them and so extinguishing its burning end.

I claim:

1. A cigarette-extinguisher, comprising a sleeve, supporting means therefor, a plunger mounted in the said sleeve and reciprocatable therein, and means co-acting with the face of the plunger for compressing the end of a cigarette, the said supporting means, plunger and compressing means being relatively arranged for the production of a clearance-space located between the plunger and compressing means and accessible through the supporting means.

2. The combination with an ash-tray, of a truncated cone rising in the center thereof to form an anvil, arms rising from the said cone on opposite sides of the said anvil, a

sleeve supported by the said arms with a clearance-space between the sleeve and the arms to permit the introduction of a cigarette horizontally over the said anvil, and a reciprocatable plunger located in line with the anvil and passing through the said sleeve for co-action with the anvil.

In testimony whereof, I have signed this specification in the presence of two subscribing witnesses.

ANTON B. MENSING.
